UNITED STATES PATENT OFFICE.

ANDREW J. UPHAM, OF STERLING, ILLINOIS.

BARB-FENCE WIRE.

SPECIFICATION forming part of Letters Patent No. 244,953, dated July 26, 1881.

Application filed March 4, 1880. (Model.)

To all whom it may concern:

Be it known that I, ANDREW J. UPHAM, a citizen of the United States, residing at Sterling, in the county of Whitesides and State of Illinois, have invented certain new and useful Improvements in Barb-Fence Wire; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a view, in perspective, from the front of the barb as placed on the fence-cable. Fig. 2 is a side elevation of the barb, the cable-wires being shown in section. Fig. 3 is a side elevation of the barb in position. Fig. 4 is a top plan, showing barb in position.

This invention relates to improvements in barbs for wire-fence cables; and the novelty consists in the peculiar manner in which the pieces which form the barb are wound upon each other and upon the cable, all as will now be more fully set out and explained.

In the accompanying drawings, A denotes a wire-fence cable; and *a a*, its strands, twisted. B is the barb, and *b b'* the pieces of wire of which it is composed. The piece *b* is wound entirely about the cable-strands, and its ends project on either side at right angles to the cable and form two of the barb-points. The piece *b'* is wound between the cable-strands, wholly around the part *b*, and its ends project from each side of the cable and also at right angles to the ends of part *b*, and form the other two points of the barb. As thus made and applied the ends of the barb will almost always stand in the uniform relation with each other as now shown in Fig. 5, where the ends of *b* point vertically up and down, and the ends of *b'* horizontally and at almost exact right angles with those of *b*.

This barb has very great advantages as a practical device. The first section winds around both main wires, holding the wire firm, leaving both ends exactly equal in opposite directions. Then the next section winds only around the first section and between the two main wires, (not outside,) its points in opposite directions, and necessarily at right angles with the first two points. This position, winding

around first section and between the main wires, protects the points of this section and prevents them from slipping or bending, and the twist of the two main wires prevents the last or middle section from bending. Thus it will be noticed the point of each is supported and leaves all the points exactly at right angles. This is very important. The barbs, having support, admit the use of No. 14 wire, which is a great saving in weight, and is more of a needle-barb than any in use, pricking but not lacerating. In this way a very uniform barb is made. It will always hold a strong and secure place upon the cable.

I am aware that structural devices have been heretofore patented consisting substantially of a staple dropped astride either a single or twisted strand or fence-wire, and having in connection therewith a second piece of pointed wire wrapped around the prongs of the riding-staple, and held in position upon the cable by the spreading apart of the prongs of the first-described staple. The integrity of this device depends upon the strength and rigidity of the riding-staple, and this is governed by the free legs of the riding-staple maintaining their position. In my device there is no staple. One wire of my barb is wrapped about both cable-wires, and the second wire of the barb is wound about this and between the cable-strand, so as to completely infold the first barb-wire and secure its permanent shape and position on the cable. Thus I have a barb with points always at right angles with each positively fixed upon the cable and capable of holding its place under any condition of use or wear.

Having thus described my invention, what I consider new, and desire to secure by Letters Patent, is—

In combination with the wire-fence cable A, the barb B, consisting of the part *b*, twisted wholly about the cable, and the part *b'*, twisted between the cable-wires and wholly around part *b*, substantially as and for the purposes set forth.

In testimony whereof I affix my signature in presence of two witnesses.

ANDREW J. UPHAM.
